(57) **CLAIM**

We claim the ornamental design for a bug-leg cane, as shown and described.

DESCRIPTION

FIG. 1 shows a general perspective view of the invention in an unfolded configuration.

FIG. 2 shows a left-side view of FIG. 1.

FIG. 3 shows a rear view of FIG. 1.

FIG. 4 shows a right-side view of FIG. 1.

FIG. 5 shows a top view of FIG. 1.

FIG. 6 shows a general perspective view of the invention in a folded configuration.

FIG. 7 shows a left side view of FIG. 6.

FIG. 8 shows a rear view of FIG. 6.

FIG. 9 shows a right-side view of FIG. 6.

FIG. 10 shows a top view of FIG. 6; and,

FIG. 11 shows a bottom view of FIG. 6.
